(57) **CLAIM**

We claim the ornamental design for edge of a magnetic sheet, as shown and described.

DESCRIPTION

FIG. 1 is a front perspective view of edge of a magnetic sheet of the present invention;

FIG. 2 is a front view thereof;

FIG. 3 is a right side view thereof;

FIG. 4 is a left side view thereof;

FIG. 5 is a top view thereof, wherein the bottom view is a mirror image thereof;

FIG. 6 is a rear view thereof; and,

FIG. 7 is a magnified view of the area of the right side bounded by 7—7 in FIG. 2.

The broken lines in the FIGS. 1, 2, 4, 5 and 6 views are for illustrative purpose only and form no part of the claimed design. The broken lines in the FIG. 7 view show the point at which the magnified, partial view is cut off, and also form no part of the claimed design.
